William Bradbury
McGall & Prince Atys

UNITED STATES PATENT OFFICE.

ROBERT F. BRACKE, OF CHICAGO, ILLINOIS, ASSIGNOR, BY MESNE ASSIGNMENTS, TO
CURTIS B. CAMP, TRUSTEE, OF OAK PARK, ILLINOIS.

SUCTION-PRODUCING MEANS FOR FUEL-FEEDING SYSTEMS.

Application filed April 13, 1923. Serial No. 631,822.

My invention relates to suction producing means for fuel feed systems for automobiles, and has for its general object the provision of improved means for lifting fuel from a fuel supply tank to a carburetor mounted above the tank.

In the accompanying drawings:

Figure 1 is a side elevational view of an automobile chassis showing the system of my invention;

Figure 2 is an end elevational view of the vortex ejector employed in the system of my invention;

Figure 3 is a vertical cross sectional view taken along the line 3—3 of Figure 2, looking in the direction indicated by the arrows; and

Figure 4 is a fragmentary cross sectional view showing a modified form of ejector nozzle.

Similar characters of reference refer to similar parts through the several drawings.

Referring first to Figure 1, 5 designates an automobile frame, 6 an engine mounted therein, 7 the radiator and 8 the fuel supply tank mounted at the rear of the car and below the carburetor 9. Mounted above the carburetor 9 is the usual form of vacuum feed tank 10 arranged to draw fuel from the tank 8 through the pipe 11. From the tank 10 the fuel is permitted to flow by gravity to the carburetor 9. All of the foregoing is well-known construction and needs no further explanation.

My invention relates to the means for producing the suction or reduction in pressure necessary in the operation of the vacuum feed tank and comprises the use of a vortex ejector in the water-circulating system of the engine. In Figure 1, 12 designates a vortex ejector forming part of the water-circulating system extending between the

engine water jacket and the radiator. As shown in Figures 2 and 3 this ejector is made up of a casing 13 arranged to provide 45 a vortex chamber 14, a water inlet 15 tangent to the chamber 14, and a water outlet 16 concentric with the chamber. Extending into the chamber 14 and concentric therewith is an ejector or nozzle 17 arranged for 50 a pipe fitting at 18 for the purpose of communicating the suction produced at the nozzle to the vacuum feed tank, as shown at 19 in Figure 1.

In the operation of the device, the cooling water is forced tangentially into the chamber 14 and, because of the centrifugal force produced by the vortex or whirl-pool action of the water, produces a high suction at the nozzle which is used to lift fuel, as 60 described.

In Figure 4 I have shown a modified form of nozzle 17' with suction holes radiating from the center.

Having thus described my invention, what 65 I claim is new and desire to secure by Letters Patent of the United States is:

A suction producing device adapted to be inserted in the pressure circulating water system of an internal combustion engine, 70 comprising a vortex conduit having intake and discharge openings and conformed to receive water tangentially from the intake opening and imparting a spiral motion thereto, the conduit having an increasing 75 constriction longitudinally from the intake for progressing the water with increased velocity toward the discharge end of the casing in its spiral movement, and a suction duct terminating adjacent the region of increased velocity for supplying suction.

In witness whereof, I hereunto subscribe my name this 27th day of March, 1923.

ROBERT F. BRACKE.
